UNITED STATES PATENT OFFICE.

NESS E. CARSTENSEN, OF CEDARBLUFFS, NEBRASKA.

PINCERS.

No. 807,240.

Specification of Letters Patent.

Patented Dec. 12, 1905.

Application filed May 10, 1905. Serial No. 269,762.

To all whom it may concern:

Be it known that I, NESS E. CARSTENSEN, a citizen of the United States of America, residing at Cedarbluffs, in the county of Saunders and State of Nebraska, have invented 5 new and useful Improvements in Pincers, of which the following is a specification.

My invention relates to an improvement in tools of the plier type, designed primarily for 10 use in repairing the links of sprocket-chains or the like.

The main object of the invention is the provision of means in the tool of the class described for readily disconnecting or connecting 15 the links of a sprocket-chain to permit the repair of such links or insertion of new ones.

The invention in its preferred form of construction will be described in the following 20 specification, reference being had particularly to the accompanying drawings, in which—

Figure 1 is a perspective view of my improved tool. Fig. 2 is a side elevation of the 25 same, illustrating its use in connecting the links of a sprocket-chain. Fig. 3 is a similar view illustrating the use of the tool for disconnecting the links of a sprocket-chain.

Referring to the drawings, wherein like 30 numerals of reference designate like parts throughout the several views, my improved tool comprises two handle members 1 and 2, terminally provided with offset disk portions 3, arranged to be pivotally connected by a 35 suitable pivot-pin 4. Forward of the pivotal connection the handle 1 is provided with what I term the "bed" of the tool, designed to receive and support the link in operation. The member comprises an arcuate body portion 5 of a width equal to the combined width 40 of the disks 3 and formed on its upper edge with an approximately S-shaped face 6. An anvil 7 of less width than the body 5 projects forwardly therefrom, formed with a concaved 45 face 8 immediately forward of the face 6 of the body portion, the curvature of which face 8 is approximately concentric with the curvature of the end of the link. The anvil terminates in a projection 9, rising above the face 8, 50 to provide a bearing-point for the links, as hereinafter described. The handle 2 forward of its pivotal connection is formed with a squared head 10, also of a width equal to the full width of both disks 3 and formed on its 55 lower face to conform to the face of the bed 6,

as at 11. The head terminates in vertical alinement with the forward edge of the face 6, providing an operating edge 12, immediately overlying the extreme forward edge of the bed. 60

The upper surface of the head 10 is squared, as at 13, to serve the usual function of a hammer. Immediately in rear of the disks 3 each handle is provided with a squared steel block 14, respectively offset to register their proximate edges, whereby to provide a wire-cutter of usual construction. The rear end of the handle 1 is shaped to provide a screwdriver 15, while the rear end of the handle 2 is bifurcated to provide a tack-puller 16. 70

In operation of my improved tool as a link-connector the body of the link to be joined in the chain, as 18, is arranged to straddle the ends 7, with its side bars abutting against the shoulders 19, formed at the junction of 75 the bed 5 and the anvil 7. The end link 20 of the chain is placed over the projection 9 of the anvil with its end bar inserted in the lap-strip 21 of the link 18. A depression of the head 10 through suitable operation of the handles 1 and 2 will cause the operating edge 12 of said head to contact with the end of the lap-strip 21 and bend the same about the end bar of the link 20, thus connecting the links. A link, as 22, to be disconnected is arranged 80 with its connected end resting approximately in the face 8 of the anvil and the end of its lap-strip 23 immediately beneath the operating edge 12 of the head 10, the body of the adjacent link 24 in the chain straddling the projection 9 of the anvil. Pressure upon the handles 1 and 2 will cause the operating edge 85 of the head 10 to open at the lap-strip of the link 22, and thereby permit its ready disconnection of the link 24. It will be noted that 90 in both operations the head of the link is supported by the face 6 of the bed-plate and by the face 8 of the anvil and that said link-head is maintained in position and against upward movement by the projection 9 of the 95 anvil 7. 100

In the use of my improved tool links may be readily connected to or disconnected from the sprocket-chain, the sole requirement for perfect operation being the positioning of the 105 link with relation to the head and to the anvil 7. The other adjuncts described in connection with my improved tool serve their usual and ordinary functions, and no detail description thereof is deemed necessary herein. 110

Having now described my invention, what I claim as new, and desire to secure by Letters Patent, is—

1. A tool of the class described comprising 5 connected members, one of said members being formed with a head and the other of said members being provided with a curved bed to coöperate with the head and with an anvil projecting forward of the bed, the head of the 10 first-mentioned member being shaped to conform to the shape of the bed, and terminating in vertical alinement with the forward edge of the bed.
2. A tool of the class described comprising 15 connecting members, one of said members being provided with a head, the other of said members being provided with a curved bed to coöperate with the head and with an anvil of less width than the width of the bed, said 20 anvil projecting forwardly from the bed and terminating in a plain face slightly above the plane of the bed, the head of the first-men-

tioned member being shaped to conform to the shape of the bed and terminating in vertical alinement with the forward edge of the 25 bed.

3. A tool of the class described comprising pivotally-connected handle members, one of said members being provided forward of the pivot with a bed having a curved face, and 30 with an anvil projecting forwardly of the bed and formed with a concaved face and with a vertically-projecting portion, the other of said members being provided with a head terminating in alinement with the forward edge 35 of the bed and formed with a face curved to conform with the face of the bed.

In testimony whereof I affix my signature in presence of two witnesses.

NESS E. CARSTENSEN.
